UNITED STATES PATENT OFFICE.

PHILIP FORSCHLER, OF NEW ORLEANS, LOUISIANA.

VEHICLE.

1,052,231.

Specification of Letters Patent. Patented Feb. 4, 1913.

Application filed April 8, 1912. Serial No. 689,168.

To all whom it may concern:

Be it known that I, PHILIP FORSCHLER, citizen of the United States, residing at New Orleans, in the parish of Orleans and State of Louisiana, have invented new and useful Improvements in Vehicles, of which the following is a specification.

My present invention has to do with vehicles; and it consists in the peculiar and advantageous construction hereinafter described and claimed.

In the accompanying drawings: Figure 1 is a side elevation of the vehicle constituting the best practical embodiment of my invention that I have as yet devised. Fig. 2 is an end elevation of the vehicle. Fig. 3 is an inverted plan showing the positions of the parts of the vehicle when the same is moving in a straight line.

Similar letters of reference designate corresponding parts in all of the views of the drawings.

The body frame of my novel vehicle comprises two longitudinal bars O, of angular form in cross-section, cross-bars Z extending between and fixedly connected to the longitudinal bars, depending supports Y of which there are preferably two employed, one adjacent each end of the body frame, and depending supports Y², of which there are four employed, one of the supports Y being arranged between and spaced from two of the supports Y², as clearly shown in Fig. 1. The supports Y and Y² are fixedly connected at their ends to the longitudinal bars O, and the intermediate portions of the said supports are suitably connected in fixed manner to the upper members of fifth wheels C. It will be understood in this connection that my novel vehicle comprises two fifth wheels, one adjacent each end of the vehicle, and that three of the supports mentioned are interposed between and connected to the upper member of each fifth wheel and the frame bars O; and it will also be understood that the supports Y² are shaped differently from the supports Y, Fig. 2, so as to enable the supports Y to brace the supports Y² and vice versa.

The gears disposed under and fixedly connected to the lower members of the fifth wheels are identical in construction, and therefore a detailed description of the gear shown in Fig. 2 and at the left of Figs. 1,

and 3 will suffice to impart a definite understanding of both. The gear specifically referred to comprises an axle G, ground wheels H at the ends of the same, hangers E straddling the axle G at points adjacent the wheels and having plates N disposed below the axle and also having bolt-receiving apertures in said plates and further having eyes P disposed above the axle, hangers F connected by bolts a, which extend through the said apertures, with the hangers E; leaf-springs I disposed in vertical planes at opposite sides of the axle G and having their ends arranged between and connected to the hangers F, as best shown in Figs. 1 and 2, hounds A fixed to the lower member 70 of the fifth wheel, bolsters V interposed and secured between the springs I and the lower fifth wheel member, clips or shackles R secured on the axle G and receiving the ends of the plates N to secure the latter against 75 the under side of the axle, and braces S interposed between and connected to the eyes P and the hounds A, and having for their purpose to prevent shifting of the axle and the imposition of undue strain on the 80 springs I. The eyes P may be formed integral with the hangers E without involving departure from the scope of my claimed invention, though I prefer to form the said eyes on plates, as best shown in Fig. 1, and 85 to connect the said plates to the hangers E. It will also be noticed in this connection that the eyes b of the plates N receive the bolts a, Figs. 1 and 2, and hence the said bolts a effect connection of the plates N to the 90 hangers; and it will further be noticed by reference to Fig. 1 that there are four hangers F employed in combination with each hanger E, the said hangers F being arranged at opposite sides of each end of 95 each spring I. In addition to the elements mentioned, the gear specifically referred to comprises a drawbar or coupling bar suitably fixed in conventional or any other approved manner between the hounds A and 100 the lower member of the fifth wheel.

By virtue of the construction of the gears at the opposite ends of the vehicle and the manner of mounting the body frame on the said gears, it will be manifest that the body frame and the body that is used thereon will be efficiently cushioned by the springs, and this notwithstanding the body frame is ar-

ranged close to the ground which is always advantageous in a vehicle irrespective of the type thereof.

It will also be manifest from the foregoing that the axles G, the springs I, and the means described associated with the axles and the springs are so constructed and arranged that notwithstanding the efficient cushioning of the fifth wheel and the body 10 frame by the two springs employed in connection with each axle, the construction is strong and durable and is well adapted to withstand the rough usage to which vehicles of the dray type are ordinarily subjected.

15 Interposed between and connected to the axles G are bars J which are crossed, as shown in Fig. 3 so as to simulate the letter X. At their ends the said bars J are pivotally connected to the axles G, as indicated 20 by L, and it will also be understood that while the bars J are crossed, they are not connected to each other, but on the other hand there is a clearance space between the bars as clearly appears in Fig. 1, this in 25 order to permit free play of each bar independently of the other bar and without the creation of friction and its attendant wear by and between the bars.

By virtue of the employment of the bars 30 J, it will be readily understood that when one of the axles is swung with its gear in a horizontal plane to bring about a turning of the vehicle, the other axle and its gear will be swung in a horizontal plane and to a corresponding extent so as to contribute to the 35 making of the turn. From this it follows that the interposition of the bars J between the swinging gears at opposite ends of the vehicle adapts the vehicle to be sharply 40 turned or to make a short turn without liability of the vehicle being upset.

As before stated, the vehicle may be drawn either by draft animals or by a motor vehicle, and the draft means can be attached 45 to the tongue B at either end of the vehicle. This will be appreciated as an important advantage when it is stated that when the vehicle is situated in a road so narrow that the vehicle cannot be turned around, all that 50 is necessary to move the vehicle backward is to disconnect the draft means from one end of the vehicle and attach such draft means to the other end of the vehicle.

In the foregoing connection I would have 55 it distinctly understood that the ends of the crossed bars J may be connected with pivoted axles of any suitable construction and

equipped or not equipped with springs without involving departure from the scope of my invention as claimed.

60

It will be readily understood by comparison of the figures of the drawings that stay braces D are connected to the under sides of the hounds A and are carried below the intermediate portions of the leaf springs D, 65 and are connected with the springs by means of shackles or other appropriate devices, as indicated by d.

The bars J are formed in part of wood 70 and in part of metallic sockets K which receive and are fixed to the wood portions and have flattened portions, disposed on and pivoted to the axles, as indicated at L.

Having described my invention, what I 75 claim and desire to secure by Letters Patent, is:

In a vehicle, the combination of a frame, upper fifth wheel members disposed below and spaced from the end portions of the frame, supports extending transversely of 80 the vehicle and spaced apart; the said supports being in two groups and each group comprising supports fixed to and extending outward and upward from the upper fifth wheel member to the frame and other supports fixed to the upper fifth wheel member at points outward beyond the lower portions of the last mentioned supports and extending upward to the frame at acute angles to 85 said supports, whereby the supports in each group are adapted to brace each other, lower fifth wheel members connected with the upper fifth wheel members, hounds disposed below and fixed to the lower fifth wheel members, axles bearing ground wheels, 90 springs extending transversely of the vehicle and connected at intermediate points in 95 their lengths with the hounds, braces interposed between and connected with the hounds and the outer portions of the axles 100 and adapted to prevent shifting of the axles and the imposition of undue strain on the springs, means connecting the springs with the axles, and crossed bars interposed between the axles and pivotally connected at 105 their ends on the end portions of the axles.

In testimony whereof I have hereunto set my hand in presence of two subscribing witnesses.

PHILIP FORSCHLER.
